(57) **CLAIM**

The ornamental design for a sanitation tablet, as shown and described.

DESCRIPTION

FIG. 1 is a perspective view of a sanitation tablet, showing my new design;

FIG. 2 is a second perspective view thereof, in an open configuration;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-sectional view thereof taken along line 9-9 of FIG. 2.
